Attorney

UNITED STATES PATENT OFFICE.

ROY R. QUACKENBUSH, OF GRAND RAPIDS, MICHIGAN.

CAN OPENER.

Application filed August 1, 1922. Serial No. 579,006.

To all whom it may concern:

Be it known that I, ROY R. QUACKENBUSH, a citizen of the United States, residing at Grand Rapids, in the county of Kent and State of Michigan, have invented a new and useful Can Opener, of which the following is a specification.

This invention relates to can openers, one of the objects being to provide a simple and efficient device which is readily adjustable to cans of different sizes and which can be used for opening cans without danger of injury to the user.

Another object is to provide a device of this character which is cheap to manufacture, durable, and will not readily get out of order.

With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings the preferred form of the invention has been shown.

In said drawings

Figure 1 is a side elevation of the device.

Figure 2 is a bottom plan view thereof.

Figure 3 is an end elevation.

Figure 4 is a perspective view of the adjustable member.

Referring to the figures by characters of reference 1 designates an angular bar having an upstanding yoke 2 fixedly connected to the end portions thereof and provided with a grip or handle 3 lying substantially parallel with the bar. A prong 4 is extended downwardly from the center of the bar 1 and constitutes the pivot member about which the device rotates while in use.

Adjustably mounted on the bar 1 is an angular sleeve 5 and mounted in one side of this sleeve is a set screw 6 which is adapted to bind against the side of the bar 1 and thus hold the sleeve 5 against sliding movement. An angular cutting blade 7 is struck downwardly from the sleeve 5 or is otherwise formed thereon.

When it is desired to open a can the prong 4 is forced in the center of the top thereof. Previously to this, however, the sleeve 5 is adjusted along the bar 1 until the blade 7 is brought to the point where the cut is to be made. The set screw 6 is then tightened to hold the sleeve against further movement. Thus when the prong 4 is forced downwardly into the can the blade 7 will also be forced thereinto. After the parts are thus arranged the device can be rotated about the prong 4 as a pivot and the blade 7 will cut through the can so as to sever the top thereof.

What is claimed is:—

In a can opener the combination with a bar, of a yoke fixedly connected at its ends to the end portions of the bar, a handle carried by the yoke, a prong fixed to and extending from the center of the bar, a sleeve embracing and slidably mounted on the bar, said sleeve being insertible onto either end of the bar, and movable from the prong to the end of the bar, the top of the sleeve being opened to pass the yoke, a cutting blade struck from and integral with the sleeve, and means carried by the sleeve for engaging the bar to hold the sleeve against movement along the bar.

In testimony that I claim the foregoing as my own, I have hereto affixed my signature in the presence of two witnesses.

ROY R. QUACKENBUSH.

Witnesses:

CHARLIE RAULIGH,
HARVEY SKINNER.
